[57] CLAIM

The ornamental design for a vehicular handset tele-
phone control unit or similar article, as shown and de-
scribed.

DESCRIPTION

FIG. 1 is a top, front, and left side perspective view of
a vehicular handset telephone control unit or similar
article showing our new design in full lines, with the
broken line matter being for illustrative purposes only
and forming no part of the claimed design;

FIG. 2 is a right side elevational view thereof;

FIG. 3 is a rear elevational view thereof; and

FIG. 4 is a bottom plan view thereof.

FIG. 1

FIG. 2

FIG. 3

FIG. 4
